UNITED STATES PATENT OFFICE.

EDWARD SEITZ, OF PEORIA, ILLINOIS, ASSIGNOR OF ONE-HALF TO JAMES E. LOCKWOOD, OF PEORIA, ILLINOIS.

VAPOR-GENERATOR.

1,081,255.

Specification of Letters Patent.

Patented Dec. 9, 1913.

Application filed July 30, 1909. Serial No. 510,438.

To all whom it may concern:

Be it known that I, EDWARD SEITZ, a citizen of the United States, residing at Peoria, in the county of Peoria and State of Illinois, have invented certain new and useful Improvements in Vapor-Generators; and I do hereby declare that the following is a full, clear, and exact description of the invention, which will enable others skilled in the art to which it appertains to make and use the same.

This invention relates to improvements in vapor lamps and vapor lamp systems and pertains particularly to a vapor generator for the same.

It is customary to provide for generators of this class a filling or packing of asbestos, metal filings, gravel stones or other noncombustible material kept highly heated where- 20 by the hydrocarbon fluid which spreads over and through it and thus contacts with a large heating surface will rapidly vaporize. This method, however, is more or less troublesome in that the heavy oils left after 25 vaporization takes place clog the packing and interfere with the proper operation of the lamps and it is necessary from time to time to remove and thoroughly clean the parts.

30 It is the purpose of this invention therefore to substitute for the older form of generator one of a different type and one that will give no trouble of this kind and at the same time will be thoroughly efficient.

35 The invention includes a hydrocarbon-gas generator wherein a liquid hydrocarbon, such for instance, as gasolene, is supplied to a vaporizing device having a heating burner, or its equivalent, by which the said 40 vaporizing device is heated, and a conduit for carrying into and directly depositing upon a superheated body the fluid to be vaporized. The fluid is not injected into the generator from a point outside it but is carried into it and deposited after being initially heated, since the conduit carrying the fluid derives heat from the heated generator.

In order that the invention may be clearly understood I have provided the accompanying drawing in which:—

Figure 1 is a vertical sectional elevation

of the generator and its parts. Fig. 2 is a longitudinal section of a part of the generator shown in Fig. 1 but on a much larger scale. Fig. 3 is another form of the same 55 part. Fig. 4 is a horizontal section of a fitting on line *a a* Fig. 1. Fig. 5 is a vertical transverse section of a portion of an inlet valve shown in Fig. 1.

A indicates a conduit leading to a lamp 60 or a series of them into which vapor is discharged from the generating portion of the apparatus about to be described, and B is a branch pipe connected into the conduit A and terminating in a tubular fitting C which 65 has an enlargement D to be more fully described later. From said fitting depends a conduit E provided at F with a regulating valve, said conduit terminating in an up-turned extension G provided with a burner 70 H in a manner common to many devices of this character. Above said burner is a vessel J which may be termed a retort and which is preferably a hollow casting from opposite sides of which project hollow ex- 75 tensions K L, the former connecting into or forming a part of a pipe M provided with a discharge orifice N controlled by a needle N' and through which vapor is supplied to the conduit A of the lamp system, 80 there being any usual mixing tube O interposed between the orifice and said conduit to which however I attach no claim to novelty herein. The vessel or retort J is closed at its top except for a threaded aperture P 85 which receives a threaded plug Q and through this aperture the interior of said vessel may be reached. The hollow extension L already referred to is preferably provided with an enlargement L' having a 90 flat face L² to abut against an end wall of the fitting C above mentioned. This wall and the opposite one each has an opening R therein in line with the bore of the extension L to receive a pipe S provided with a screw 95 threaded part at T to engage the enlargement L'. The pipe S also has a threaded portion at U to receive a nut V which serves to firmly clamp the fitting C against the said enlargement L'. The extreme end of 100 the thread-portion U receives one end of a tubular member W of a valve 2 which com-

prises said member W and a tubular portion 3 at right angles thereto all being cast as a single part as shown in section in Fig. 5. The opposite end of the portion W is provided with screw-threads to receive the threaded portion of a needle 5 which extends into the tube S, and a cap 6 together with a suitable packing 7 constitutes a stuffing box to prevent leakage around said needle.

In the wall of the part W is an aperture 8 which communicates with the bore of the portion 3 described, the latter having an interior wall 9 provided with an aperture 10 closed by a needle 11 which is provided with screw threads and engages the threads of an aperture 12 in an interior wall 13 of said portion 3, a cap 14 and a packing 15 being provided to prevent leakage around the needle. A pipe for carrying hydrocarbon fluid is suitably attached to one end of the portion 3 and is indicated by the numeral 16. The pipe S which forms a part of the present invention terminates within the vessel or retort J preferably in the top of the latter near its center. Its extremity within the vessel terminates in a thick wall indicated by S' in which a notch S² is created leaving a thin wall adjacent to the bore of the tube which has a jet orifice 17 controlled by the needle 5 hereinbefore described, Fig. 3 showing a tube S⁴ for the purpose provided with an aperture S⁵ but without a needle. However, since the jet orifice is entirely inclosed in the vessel J it cannot be cleared of deposits as can be done with orifices in other types of this class of device, in the present instance the needle 5 is preferably arranged to enter and directly control the orifice and it serves to keep said orifice perfectly free and open. The hydrocarbon fluid in the pipe 16 passes the needle 11 into the portion 3 and enters the portion W through the aperture 8 thence passing into the pipe S and out through the orifice 17 into the vessel or retort J the latter containing preferably, though not of necessity, a filling of asbestos or other suitable material J'. The vessel J being heated by the burner H vaporizes the fluid introduced into it and this is carried to the lamp system through the conduit A and to the said burner H through the conduit B. An annular space surrounds the pipe S within the tubular extension L and the heat from the metal of the latter serves to heat the pipe S through said space sufficiently to raise the temperature of the fluid in the tube S so that being already hot it will, when discharged from the orifice 17, be instantly vaporized. A depending limb S³ of the wall S' of the pipe S created by the notch S² serves to deflect the hydrocarbon fluid downward into the vessel J. In addition to heating the pipe S through the medium of the

heat within the space of the extension L the heated vapor in passing through the pipe B to the burner H impinges upon the said tube within the tubular fitting C in passing around said pipe and this also aids in raising the temperature of the fluid.

An advantage arises in constructing the fitting C as shown in Figs. 1 and 4 in that the pipe S can be placed centrally of the bore of the extension L by means of the enlargement L' and the latter and the nut V and its parts may all be firmly clamped together in proper position and can be quickly detached when making repairs and the parts can all lie in one plane and thus present a neater appearance than would otherwise be the case. The form of the valve 2 permits the needles 5 and 11 to extend past one another at right angles and the passages to communicate with one another through the orifice 8, one of the valves governing the flow of fluid from the pipe 16 and the other governing the discharge orifice 17.

My structure precludes the necessity of employing filling materials within pipes that carry the hydrocarbon by depositing said hydrocarbon directly into a large highly heated member wherein it is quickly and thoroughly vaporized the parts requiring, therefore, little or no attention.

Having thus described my invention, I claim.

1. In an apparatus of the class described the combination of a vapor generator, a vapor discharge nozzle communicating therewith, a pipe extending into said generator and having an opening at its inner end for the discharge of a combustible fluid, a conduit including a mixing chamber for air and vapor communicating with the said nozzle, a burner beneath the generator and a pipe connecting the conduit with the burner and having the first named pipe extending therethrough.

2. The combination with a pipe, of a vapor generator with which the pipe is connected, a conduit for vapor communicating with said generator, a second pipe leading from the conduit and terminating with an open end beneath the generator, said pipe having the first named pipe extending laterally and substantially centrally therethrough.

3. The combination with a vapor generator, of a conductor for vapor communicating therewith and leading to and terminating beneath the said generator, and a pipe for a combustible fluid smaller in diameter than the conductor and extending laterally through the same into the generator and separated from the walls of the said conductor by a space whereby the vapor in said conductor is made to flow around said pipe.

4. The combination with a vapor generator consisting of a hollow member, a tubular fit-

ting adjacent to and abutting against an extension of said generator, a pipe extending through the fitting and in engagement with it and the said extension of the generator, and terminating within the latter.

5. The combination with a vapor generator consisting of a member provided with a cavity and a tubular extension communicating with said cavity, of a tubular fitting abutting against said tubular extension, a pipe extending through the fitting and in engagement with it and extending also into the said tubular extension and engaging the same and terminating within the cavity of the generator.

6. The combination with a vapor generator consisting of a member provided with a cavity and a tubular extension communicating therewith, of a tubular fitting abutting against said extension, a pipe extending through the fitting and terminating within the cavity and having a jet orifice having threaded engagement with the tubular extension, means to engage the pipe and adapted to bear upon the fitting to clamp it to the extension, and a needle valve extending through the pipe and into and having control of the said jet orifice.

7. The combination in a lighting system including a vapor pipe, of a vapor generator consisting of a member provided with a cavity, a jet orifice adapted to discharge into said pipe, said generator also including a tubular extension, a pipe threaded into said extension and terminating at one end in a jet orifice within the cavity, and supplied outside said generator with a combustible fluid, and a needle-valve extending through the pipe to and in control of the last named jet orifice.

8. The combination in a lighting system including a vapor pipe, of a vapor generator consisting of a member provided with a cavity and a hollow extension communicating with said cavity, said generator including a jet orifice adapted to discharge into said pipe, a fuel supply pipe extending into said extension and closing its outer end, said pipe terminating in a jet orifice within said cavity and supplied with a combustible fluid outside the generator, and a needle-valve extending through the pipe, to and in control of the last named jet orifice.

9. The combination of a vapor generator, a pipe extending into it for the introduction of a combustible fluid, a burner to heat the generator, means to conduct vapor from the generator to said burner, the said pipe extending transversely through the said means and lying in the path of the vapor.

10. The combination of a vapor generator, a pipe extending into and terminating in said generator and provided with a discharge orifice at its end within said generator, a burner for heating the generator,

means to conduct vapor from the generator to said burner and having the pipe extending transversely therethrough, and a needle-valve extending into and in control of the discharge orifice.

11. The combination of a vapor generator, a pipe extending into and lying within the same and separated from its walls by a space and having a discharge orifice at its extremity within the generator, a vapor conductor for receiving vapor from said generator and through which the pipe extends laterally, and a burner carried by the said conductor.

12. The combination of a vapor generator having a tubular extension at one side, a pipe lying within said extension and extending into the generator and separated from the extension by an annular space and having a discharge orifice at its extremity within the generator, a conductor arranged to receive vapor from the generator through which the said pipe extends transversely, and a burner carried by said conductor.

13. The combination of a vapor generator having a tubular extension at one side, a pipe lying within said extension and extending into the generator and separated from the extension by an annular space and having a discharge orifice at its extremity within the generator, a conductor for vapor through which the said pipe extends transversely, a burner carried by said conductor, and a needle-valve in control of the discharge orifice.

14. The combination with a vapor generator and an extension thereof, of a hollow fitting lying adjacent to and against said extension, a vapor burner beneath the generator and in communication with said hollow fitting a pipe arranged to receive vapor from the generator and connected with said fitting, a second pipe extending through said hollow fitting across the path of vapor carried thereby and in threaded engagement with the fitting and extending into and terminating in said generator, and a lock-nut carried by said second pipe in engagement with the fitting.

15. A vapor generator comprising a hollow member having a depending hollow extension, a burner beneath the extension and communicating with and receiving vapor from said generator, a pipe extending into and terminating within the latter for conveying combustible fluid thereto and having a discharge orifice in its terminus within the hollow extension, a valve to control said orifice, and means opposite the orifice to direct the fluid discharge therefrom into the extension.

16. In a device of the class described, a vapor generator, a burner beneath the same, means to conduct vapor from the generator to said burner, a pipe extending through

the conducting means into the generator and having a discharge orifice at its inner end within the generator, said generator and the pipe and said means having rigid connected relation, and a single valve-body connected with the pipe and with a supply pipe and having means for regulating the flow of fluid from said supply pipe; and

means for directly controlling the discharge orifice in the first named pipe. 10

In testimony whereof I affix my signature, in presence of two witnesses.

EDWARD SEITZ.
